UNITED STATES PATENT OFFICE.

JOHN OSS, OF ATLANTA TOWNSHIP, BECKER COUNTY, MINNESOTA.

COMPUTING-MACHINE.

1,022,590.

Specification of Letters Patent.

Patented Apr. 9, 1912.

Application filed February 20, 1911. Serial No. 609,733.

To all whom it may concern:

Be it known that I, JOHN OSS, a citizen of the United States, residing in the township of Atlanta, in the county of Becker and 5 State of Minnesota, have invented certain new and useful Improvements in Computing-Machines; and I do declare the following to be a full, clear, and exact description of the invention, such as will enable others 10 skilled in the art to which it appertains to make and use the same.

This invention relates to improvements in computing machines.

One object of the invention is to provide 15 a computing machine having an improved means for accurately adding and subtracting any series of numbers.

Another object is to provide a machine of 20 this character having arranged thereon a printing attachment whereby the numbers to be added and the result obtained may be printed or recorded.

A further object is to provide a computing machine for adding and subtracting 25 numbers and having connected thereto a multiplying and dividing mechanism.

With these and other objects in view, the 30 invention consists of certain novel features of construction, combination and arrangement of parts as will be more fully described and particularly pointed out in the appended claims.

In the accompanying drawings: Figure 1 is a plan view of my improved computing 35 machine; Fig. 2 is an elevation of one end thereof; Fig. 3 is a vertical sectional view on the line 3—3 of Fig. 1; Fig. 4 is a vertical cross sectional view on the line 4—4 of Fig. 3; Fig. 5 is an irregular vertical 40 sectional view on the line 5—5 of Fig. 4; Fig. 6 is a horizontal sectional view on the line 6—6 of Fig. 4; Fig. 7 is a similar view on the line 7—7 of Fig. 4; Fig. 8 is a detail side view of one end of the main portion of 45 the machine showing the manner in which the multiplying and dividing mechanism is attached thereto; Fig. 9 is a detail vertical sectional view through one end of the paper supporting devices of the printing mechanism 50 taken on the line 9—9 of Fig. 10; Fig. 10 is an end view of the paper holding devices of the printing mechanism shown in Fig. 9; Fig. 11 is a vertical cross sectional view of the same parts on the line 11—11 of 55 Fig. 9; Fig. 12 is an enlarged fragmentary

horizontal sectional view of the adjoining parts of the adding and subtracting mechanism and the multiplying and dividing mechanism showing the manner in which the latter is operated by the former. 60

In the embodiment of the invention as shown in the accompanying drawings, I provide a casing 1 which may be of any suitable shape and is here shown in the form of a rectangular box having in its upper side a longitudinal opening 2 and in its ends are formed openings 3. In the opposite sides of the casing 1 are arranged computing devices which for convenience will be hereinafter designated as tallies 4 and 5, said tallies 4 and 5 comprising longitudinally disposed rectangular oblong casings which are hingedly connected at one end to the adjacent end of the outer casing 1 as shown at 6. In the casings 4 and 5 are arranged a series of computing gears which will be hereinafter described. 75

Revolutely mounted in the bottom of the outer casing 1 is a main operating gear 7, said gear being revolutely mounted in horizontal position on a pivot screw in the lower portion of the casing as shown. The gear 7 has formed integral therewith a concentric beveled gear pinion 8 with which is engaged a similar pinion 9 fixed on the inner end of an operating shaft 10 journaled in suitable bearings in the casing 1 and having its outer end projecting through one side of the casing and provided with a crank handle 11 whereby said gear 7 may 90 be revolved in one direction or the other for operating the computing mechanism hereinafter described. The inner end of the shaft 10 is revolutely mounted in a bearing bracket 12 secured to the lower side of a longitudinally disposed supporting bar 13 arranged through the center of the casing 1 and having its opposite ends secured to the ends of the casing at the bottom of the openings 3 formed in said ends. 95

Revolutely mounted in one end of the casing of the tallies 4 and 5 are combined power transmitting and computing shafts 14 the lower ends of which project downwardly through the bottom of the tallies 4 and 5 and have fixed on their lower ends spur gear pinions 15 which are adapted to be operatively engaged with the adjacent portions of the operating wheel 7 whereby said shafts are driven. 105 110

Arranged parallel with the shafts 14 and revolvably mounted in the tallies 4 and 5 are a series of vertically disposed shafts 16 on which and the shafts 14 are mounted spur gears 17 each of which contains thirty-two teeth. On each of the gears 17 except the last gear are arranged concentrically disposed annular series of upwardly projecting pins 18 each of said series containing twelve pins. On the upper ends of the shafts 14 and 16 above the tallies 4 and 5 are fixedly mounted a series of dial operating gears 19 each of which contains ten teeth. Revolvably mounted in the tally casings 4 and 5 between the shafts 16 are a series of vertically disposed counter shafts 20. On each of the shafts 20 is fixedly mounted a spur gear 21 said gears each having thirty teeth. On each of the gears 21 is arranged an annular series of upwardly projecting pins 22 each series of which contains eight pins. When thus arranged the gears 17 on the shafts 16 will operatively engage the pins 22 on the gears 21 of the shafts 20 while said gears 21 will operatively engage the pins 18 on the gears 17 of the shafts 16, and said shafts being thus operatively connected together will be simultaneously driven by the main operating gear 7 when the pinions 15 on the shafts 14 are engaged therewith. The tally frames 4 and 5 are adapted to be swung in a horizontal plane in the casing 1 to bring the pinions 15 into and out of engagement with the gear 7 by upwardly projecting shifting posts 23 which are secured to the upper sides of the tally casings 4 and 5 and have reduced threaded upper ends which project through segmental slots 24 formed in the top of the casing 1. On the reduced threaded upper ends of the posts 23 are binding nuts 25 which are adapted to be screwed down into tight frictional engagement with the upper side of the casing thereby holding said tally frames in or out of operative position.

On the upper inner corners of the tally casings 4 and 5 are formed lateral inwardly projecting bearing plates 26 on which are revolvably mounted series of dial supporting gears 27 one of said gears being disposed opposite to and in mesh with each of the spur gears 19 on the shafts 14 and 16 of the tallies. The gears 27 each have ten teeth and are provided on their upper sides with dials 28 having thereon numerals from 1 to 10, said numerals being disposed over the teeth of the gears 27 as shown. Slidably mounted in inclined or diagonally arranged passages 29 formed in the gears 27 and dials 28 opposite each of the teeth of said gears are type plungers 30 having on their inner ends type 31 said type being disposed beneath the teeth of the gear wheels and containing the numbers indicated on the dials above the respective teeth. On the upper

ends of the plungers are arranged suitable heads between which and the upper side of the dial are arranged coiled springs 32 which normally hold the plungers and type in a retracted or inoperative position. The outer edges of the bearing plates 26 of the tallies are curved upwardly to a slight extent and said edges have formed therein opposite the center of each of the gears 27 a notch or recess 33 through which the type are adapted to be projected into engagement with the paper as will be hereinafter more fully described. On the upper surfaces of the curved edges of the plates 26 on each side of the notches 33 are arranged inkling pads 34 with which the type are engaged as the gears are turned to bring the type into position over the notches 33.

In order to support the paper in position for receiving the impressions from the type I provide a suitable paper supporting mechanism comprising a segmental roller supporting frame 35 having on its lower side a dovetail shaped rib 36 which is slidably engaged with a similarly shaped groove 37 formed in the bar 13 which connects the opposite ends of the casing 1. On the opposite ends of the frame 35 are secured end plates 38 in which are formed bearing passages 39 in which are journaled the pintles 40 of a paper supporting roller 41 arranged in the segmental frame 35 as shown. On the projecting end of one of the pintles 39 is fixedly mounted a crank handle 42 by means of which the roller may be revolved in the frame for the purpose of winding the paper 43 thereon. On the opposite end of the roller is fixedly mounted a ratchet gear 44 with the teeth of which is adapted to be engaged a plunger 45 arranged in a supporting bracket 46 secured to the adjacent end 38 of the frame. On the plunger 45 is arranged a knob or head between which and the bracket 46 is arranged a coiled retracting spring 47 whereby the plunger is retracted and normally held out of engagement with the teeth of the gear 44. By providing the plunger 45 the roller may be turned a certain distance at a time thus providing for the proper spacing of the paper for printing the lines or columns of figures.

Slidably mounted in slots 48 formed in the end plates 38 is a roller supporting rod or shaft 49 on which are arranged pressure or tension rollers 50 held in yielding engagement with the paper supporting roller 41 by springs 51 arranged on the opposite ends of the plates 38 as shown. By thus engaging the roller 50 with the paper supporting roller the latter will be prevented from being turned too far in either direction when operated by the spacing mechanism hereinbefore described. On the shaft or rod 48 is also secured a curved paper holding and guiding plate 52 having on its outer

edge bearing sleeves 53 whereby the same is pivotally mounted on the rod or shaft 49. In the plate 52 is formed a central longitudinally disposed paper guiding slot 54 along one edge of which the plate is bent downwardly to form a paper engaging flange 55 whereby the paper is held against slipping on the roller. In the guide plate on opposite sides of the slot 54 are formed longitudinally disposed type receiving slots 56 through which the type are projected by the plungers 30 and the impression of the type thus made on the paper.

In addition to the adding and subtracting mechanism hereinbefore described I preferably also employ a multiplying and dividing mechanism which is operatively connected with the adding and subtracting mechanism and comprises a tally 57 in the form of a rectangular oblong frame or casing, arranged adjacent to one end of the main casing 1 to which said tally casing 57 is hingedly connected at one corner as shown at 58. The tally 57 when thus connected is adapted to be swung into and out of operative position with respect to the main casing 1 and is adapted to be adjustably fastened at its free end to the adjacent side of the casing 1 by a latch plate 59 pivotally secured at one end to the end of the tally casing 57 and having formed near its outer end two notches 60 either one of which is adapted to be engaged with a fastening pin 61 thereby adjustably securing this end of the tally 57 to the main casing 1. The latch-plate is preferably provided on its free end with an operating knob 62.

Revolutely mounted in one end of the tally casing 57 is a vertically disposed main drive shaft 63 and a series of similarly mounted gear supporting shafts 64. On the shafts 63 at the bottom of the tally is fixedly mounted a ratchet gear 65 with which is engaged an operating pawl 66 said pawl being pivotally connected to the inner end of an operating lever 67 which is pivotally mounted on the bottom of the tally casing 57 and projects through a slot 68 formed therein and through a similar slot 69 formed in the adjacent end of the casing 1. The pawl 66 is held in operative engagement with the teeth of the ratchet gear 65 by a spring 70. The lever 67 projects into the casing 1 a suitable distance and is engaged with a recessed trip lug 71 arranged on the adjacent end of the tally 4 whereby each time said tally is swung laterally to disengage the pinion 15 of the computing mechanism therein from the main drive gear 7 the lever 67 will be tripped and the movement thereof imparted to the ratchet 65 by the pawl 66 thereby turning said ratchet to the distance of one tooth. The recess in the lugs 71 and the outer edge of the lug on each side of the recess as well as the engaging end of

the lever 67 are rounded so that these parts will play smoothly on each other and will be prevented from binding when the tally 4 is swung outwardly in the manner described. The ratchet gear 65 is held against retrograde movement by a stop pawl 72 pivotally mounted in the bottom of the tally casing 57 as shown.

On the shafts 64 are fixedly mounted a series of spur gears 73 each of which contains thirty-two teeth. On the ratchet gear 65 and on each of the gears 73 except the last are arranged annular series of concentrically disposed upwardly projecting pins 74 said gears and pins corresponding to the gears 17 and pins 18 on the shafts 16 of the tallies 4 and 5. The upper ends of the shafts 64 project through the top of the tally casing 57 and have fixedly mounted thereon circular dial plates 75 on which are arranged an annular series of numerals from 1 to 10. On the upper side of the tally casing 57 in line with the center of each of the shafts 64 is arranged a fixed pointer 76 which coacts with the numerals on the dials 75.

Revolutely mounted in the tally casing 57 between the shafts 64 are a series of vertically disposed counter shafts 77 on each of which is fixedly mounted a spur gear 78. 95 The gears 78 each contain thirty teeth and are adapted to operatively engage the annular series of pins 74 on the gears 73 each of said series containing twelve pins. Arranged on each of the gears 78 is an annular series of concentric vertically disposed pins 79 each series of which contains eight pins. The pins 79 are operatively engaged with the teeth of the gears 73 on the shafts 74 whereby said shafts are operatively connected together to turn at the proper relative distances for carrying out the multiplying and dividing operation hereinafter described. When it is not desired to employ the multiplying and dividing attachment the latch plate 59 may be released and the tally 57 swung outwardly thus disengaging the lever 67 from the trip lug 71 on the tally 4 of the adding and subtracting mechanism.

In the operation of the machine it will 115 be understood that in all three tallies the relation or ratio of the gears and shafts which operate the tallies is as 1 to 10 or in other words the arrangement of the teeth and pins of the gears on the dial operating shafts 120 and the gears and pins on the counter shafts interposed between said dial shafts will cause each successive dial shaft beginning with the shafts 14 in the tallies 4 and 5 and the shaft 63 in the tally 57 to travel ten 125 times slower than the next preceding shaft. Thus when the dials operated by the shafts 14 and 63 make one complete revolution the next or adjoining dials will be moved to the distance of but one space or unit number, 130

this relation being carried out throughout the entire series of dials. With the foregoing in mind to use the machine for adding for example the following columns of 5 numbers representing the debit and credit sides of an account. The debit, 1-5-9-2-5; 10 3-5-4-0-1-0; 5-8-6-0-6-5; credit, 1-9-4-0-5-0; 5-9-8-6-0-2; 1-1-4-3-4-8. The dials of the two 15 tallies 4 and 5 are adjusted to bring the naughts thereon opposite to the printing spaces in the frames or casings of the tallies after which both of the tallies are brought into position to engage the computing gear pinions 15 thereof into engagement with the main operating gear 7 in which position the tallies are fastened by the binding nuts 23 hereinbefore described. With the parts in this position the first number 20 1-5-9-2-5 is registered on the dials by turning the crank handle 11 in the proper direction to drive the main gear 7 and pinions 15 thus operating the series of gears in the tallies which operation is continued until the next to the last dials at the opposite 25 ends of the tallies from the driving mechanism are turned to bring the number 1 thereon opposite to the printing spaces 33 in the dial frames. When this number has 30 thus been obtained the same is printed from the tally 5 by pressing the type plunger opposite the number 1 until said number is printed on the paper of the printing roller. After this number has thus been obtained 35 and printed the gears are again operated in the manner described until each of the succeeding numbers 5-9-2-5 are brought by the successive dials opposite their printing spaces in the tally plates and are printed 40 from the tally onto the paper. After this number has thus been obtained the plunger 45 is depressed to turn the printing roller and paper to the distance of one space to receive the next number to be added. After 45 the roller has thus been shifted the machine is in readiness to be adjusted for recording the next number to be added. In the operation of adding the next number it is necessary to retain the first number on one of the 50 tallies and in order to retain this number the binding nut of the tally 4 is loosened and said tally swung laterally to disengage the computing pinion 15 thereof from the main operating gear 7 while the latter is being reversed or turned backward to bring the 55 dials of the tally 5 into their original position wherein 0 will appear opposite to the printing spaces of all the dials. After the 60 dials of the tally 5 have thus been adjusted the tally containing the first number recorded is swung back into operative engagement with the operating gear 7 and secured whereupon the machine is in readiness to record the next number 3-5-4-0-1-0. 65 With the parts in this position the operat-

ing mechanism is again started and the number 3-5-4-0-1-0 is successively registered on the dials of the tally 5 and printed on the paper in the manner described. While thus registering this number on the dials of the tally 5 the same will be added to the number previously registered on the dials of the tally 4. After this number has been thus registered and printed on the tally 5 and added to the tally 4 the latter is again swung out of engagement with the operating mechanism while the dials of the tally 5 are run back to show naught opposite the printing spaces in the tally casing whereupon the tally 4 is again 70 swung back into an operative position and the next number 5-8-6-0-6-5 is registered and printed on the dial 5 and added to the previous amount on the tally 4. The result obtained after adding the last number to the previous amount on the tally 4 will indicate the sum or total of the debit side of the account and this sum is then printed by the type of the tally 4. This sum will be shown to be 9-5-6-0-0-0. The 80 numbers on the credit side of the account are now added and recorded in exactly the same manner as described in connection with the adding of the debit side of the account and when thus added and recorded 85 will show a total of 9-0-7-0-0-0. In order to obtain the balance it is necessary to subtract the 9-0-7-0-0-0 from the 9-5-6-0-0-0 which operation may be accomplished on the machine in the following manner: The 9-0-7-0-0-0 representing the total amount of the credit side of the account is left on the tally 4 and this tally is swung out of engagement with the operating mechanism while the tally 5 is 90 operated to show 9-5-6-0-0-0 which is the total amount formerly obtained for the debit side of the account. When the dials on the tally 5 show this amount the tally 4 is swung back into engagement with the operating mechanism and the latter turned in a reverse direction until all of the dials of the tally 4 containing the smaller number will show naught opposite the printing spaces of the tally casing thus indicating 100 that all this number has been run off whereupon the number showing on the dials of the tally 5 will indicate the balance or difference between the two numbers and will be seen to be 4-6-0-0-0. By this operation 105 it will be readily seen how the machine may be employed for subtracting any number from another larger number.

In order to use the machine for multiplying and dividing it is necessary to employ 110 the third tally 57 which is connected with the tally 4 and operated by the lateral movement of the latter in the manner described. Assuming that it is desired to multiply 3-0-0-0 by 5 which is equivalent to add 115 120 125 130

ing 3—0—0—0 five times it is first necessary to have the dials of all the tallies 4 and 5 and 57 all showing naught opposite the printing spaces or in the case of the tally 5 57 opposite the pointers 76 thereon. The tallies 4 and 5 are thus both operatively connected with the computing mechanism and the lever 67 is engaged with the lugs 71 on the tally 4. With the parts in this position 10 the crank 11 is rotated and the operating or computing mechanism thus driven until the number 3—0—0—0 is added or indicated on tallies 4 and 5. After this number has thus been registered the tally 4 is swung 15 laterally out of engagement with the operating mechanism and in thus moving will trip the lever 67 and cause the pawl 66 to turn the ratchet gear 65 and shaft 63 to the distance of one tooth which will bring the 20 number 2 on the dial of the shaft 63 opposite to the pointer of said dial, the dial on the shaft 63 having been previously turned by the lever 67 during the preliminary adjustment of the tally 4 to bring the 1 thereon 25 opposite to the pointer of the dial. With the tally 4 thus swung out of engagement with the operating mechanism the latter is turned in the opposite direction until the 30 dials on the tally 5 again show naught opposite the printing spaces thereof. The tally 4 is then swung back into engagement with the operating mechanism and the latter actuated to again register 3000 on the dials of the tally 5 and to add this amount to the 35 previous 3000 recorded on the dials of the tally 4. When this number has thus been recorded the tally 4 is again swung out of engagement with the operating mechanism and in so moving will trip the levers 67 and 40 cause the same to again turn the ratchet gear 65 and shaft 63 to the distance of one tooth thus bringing the number 2 opposite to the pointer on the tally 57. The operating mechanism is then reversed to bring 45 the dials of the tally 5 back to naught after which the tally 4 is again swung into operative position and the operation of the device continued in the manner described until 50 3000 has been registered five times on the dials of the tally 5 and has been added five times on the dials of the tally 4. In this operation it will be understood that the tally 4 has been swung out of engagement with the operating mechanism five times and the 55 ratchet wheel 65 and shaft 63 turned thereby the same number of times so that the number 5 will be indicated on the dial of the shaft 63 in the tally 57. After thus completing the multiplying operation the tally 57 will 60 show the multiplier which is 5 and the tally 4 will show the product which is 15000. In this operation the various amounts obtained on the dials 4 and 5 may be printed in the 65 manner described in connection with the adding and subtracting operation.

In the operation of the device for dividing which is but a short method of subtracting equal numbers, assuming that it is desired to ascertain the number of times 3000 is contained in 15000 the tallies 4, 5 and 57 70 are adjusted to show naught at their starting points and the tally 57 is operatively connected with the tally 4 in the manner described. Before the tally 4 is connected up for operation the dials thereon are adjusted to show 15000 while the dials of the tally 5 are adjusted to show 3000. With the dials of the tallies in this position the operating mechanism is turned in a reverse direction from that in which the same is 75 turned for adding until the dials on the tally 5 are run back to show naught opposite the printing spaces thereof. In this operation the dials of the tally 4 are also run back in the same proportion so that 12000 will be 80 indicated on this tally. After this operation the tally 4 is swung out of engagement with the operating mechanism thus actuating the lever 67 and causing the same to turn the ratchet gear 65 and shaft 63 in the 85 tally 57 to the distance of one tooth thus causing the tally on said shaft 63 to show number 2 opposite the pointer of said dial, the dial having been previously turned to show the number 1 by the outward preliminary movement of the tally 4. While the tally 4 is thus swung out, the operating mechanism is actuated to again show 3000 on the tally 5. The tally 4 is then swung 90 back into engagement with the operating mechanism which is actuated in the same manner as before until the 3000 is run off from the tally 5 and this amount again deducted from the previous amount on the tally 4 which will show 9000 on this tally 100 and 0 on the tally 5. The tally 4 is then again swung out of engagement with the operating mechanism and caused to actuate the gears of the tally 57 to cause the dial on the shaft 63 to show 3. While the tally 110 4 is thus out of engagement with the operating mechanism the dial 5 is operated to again register 3000 and the dial 4 swung back into operative position when the previous operations of the device are repeated 115 until the dials on the tally 4 will show naught at which time it will be seen that the dial on the shaft 63 of the tally 57 will show 5 which will indicate that 3000 is contained in 15000 five times. 120

The invention as herein shown and described is for the purpose of adding, subtracting, multiplying and dividing. It is obvious however that the machine may be employed for various other purposes such for instance as a cash register or as a recorder for registering and printing various series or arrangements of numbers. 125

From the foregoing description taken in connection with the accompanying drawings, 130

the construction and operation of the invention will be readily understood without requiring a more extended explanation.

Various changes in the form, proportion 5 and the minor details of construction may be resorted to without departing from the principle or sacrificing any of the advantages of the invention as defined in the appended claims.

10 Having thus described my invention what I claim is:

1. In a computing machine, the combination of a casing, a master gear in the casing, an inner casing, a train of computing gears 15 in the inner casing, a vertical shaft of said train projecting above and below the inner casing, gearing connecting the lower end of the vertical shaft with the master gear, a series of disconnected revolute dials carried 20 by the inner casing, a gear attached to each dial and adapted to engage a correspondingly located gear of the train, and means for throwing the gear of the train out of connection with the master gear.

25 2. In a computing machine, the combination of a casing, a master gear in the casing, an inner casing pivotally mounted in the main casing, a train of computing gears in the inner casing, a vertical shaft of said 30 train projecting above and below the inner casing, gearing connecting the lower end of the vertical shaft with the master gear, a series of disconnected revolute dials carried by the inner casing, means for throwing 35 the gear of the train out of connection with the master gear, and means for moving the inner casing on its pivot to disconnect it from the master gear.

40 3. In a computing machine, the combination of a main casing, a master gear journaled therein, two inner casings within the main casing, a train of computing gears in each inner casing, a vertical shaft included in each of said trains projecting above and 45 below the inner casing, gearing on the lower end of each vertical shaft adapted to engage the master gear, a series of disconnected revolute dials in each inner casing, a gear for each dial of each series adapted to 50 engage a corresponding gear in its computing train, and means for throwing the gears of the train of either of the inner casings out of engagement with the master gear.

55 4. In a computing machine, the combination of a main casing, a master gear journaled therein, two independent inner casings pivotally connected to the walls of the main casing, a train of computing gears in each 60 inner casing, a vertical shaft included in each train projecting above and below its inner casing, gearing connecting the lower end of each vertical shaft independently of the master gear, a series of disconnected revolute dials carried by each inner casing, a

gear for each dial adapted to engage a correspondingly located gear of its respective computing train, means for moving either of the inner casings on its pivot to disconnect its train of gearing from the master gear, and means for securing the casings in their disconnected positions. 70

5. In a computing machine, the combination of a main casing, an inner casing pivoted to the walls of the main casing, a train 75 of computing gearing in the inner casing, a series of dials carried by the inner casing, a gear for each dial, engaging a corresponding gear in the train, a master gear wheel in the main casing, means for moving the inner 80 casing on its pivot for connecting or disconnecting each of the trains of gearing with the master wheel, an outside casing adjacent and pivoted to the main casing, a series of registering dials carried by the outside 85 casing and connections whereby the movements of the inner casing to disconnect its gear with the master wheel are registered on the dial on the outside casing.

6. In a computing machine, the combination of a main casing, a master gear therein, an inner casing pivoted to the walls of the main casing, computing gear in the inner casing adapted to be connected with or disconnected from the master gear wheel, an 90 outer casing carrying a series of registering dials including a ratchet wheel, a lever pivoted in the outer casing and projecting through its wall and the wall of the main casing, a lug on the inner casing engaging 95 one end of said lever and a spring pawl pivoted at the other end of the lever and engaging the ratchet in the outside casing. 100

7. In a computing machine, the combination of a casing provided with a lateral extension of its cover, a series of computing gearing in the casing, a series of disconnected dials journaled in the extension of the cover of the casing, a gear carried by each dial and engaging a corresponding gear in 105 the computing train, a series of numbers from 0 to 9 on each dial and an independent spring retracted type carrying plungers slidably mounted in each dial adjacent to the corresponding figures thereon. 110

8. In a computing machine, the combination of a casing, a train of computing gearing therein, a lateral extension of the cover of the casing having its outer edge inclined upwardly and provided with a series of 115 notches, paper rolls mounted below the inclined portion, a series of registering dials journaled on the extension of the cover, a pivot of each dial being in line with one of the notches and each dial being provided 120 with numbers from 0 to 9, and a series of spring retracted type plungers slidably mounted in each dial adjacent to the corresponding figure on the dial, concentric with the pivot of the dial and at the same distance 125 130

therefrom as the notch in the inclined portion of the casing cover.

9. In a computing machine, the combination of a main casing, a grooved bar mounted longitudinally therein, a substantially cylindrical casing provided with a tongue slidably fitting in the groove of the bar, said casing being open for nearly one half of its upper portion; a notched plate supported above the casing longitudinally thereof on each side of the line of its vertical center, an inking pad adjacent to each notch, a circular

dial mounted on a vertical pivot, a paper roll mounted in the cylindrical casing, and a concentric series of type plungers mounted in the dial and adapted to travel over the inking pads and register with the notches. 15

In testimony whereof I have hereunto set my hand in presence of two subscribing witnesses.

JOHN OSS.
